Roger C. Bainbridge, Novi, Mich., assignor to American Motors Corporation, Detroit, Mich., a corporation of Maryland

Filed Aug. 7, 1964, Ser. No. 81,204

Term of patent 14 years

(Cl. D49—1)

I claim:

The ornamental design for a face panel for laundry machine splash board or the like, substantially as shown and described.
